UNITED STATES PATENT OFFICE.

RICCARDO DI CARLO, OF BALTIMORE, MARYLAND.

CLIPPER.

1,353,423.

Specification of Letters Patent.

Patented Nov. 9, 1920.

Application filed August 1, 1919. Serial No. 314,610.

To all whom it may concern:

Be it known that I, RICCARDO DI CARLO, citizen of the United States of America, residing at Baltimore, in the State of Maryland, have invented certain new and useful Improvements in Clippers, of which the following is a specification.

This invention relates to improvements in clippers and the invention has for its principal object to provide a pair of automatic or motor driven clippers capable of being operated at a speed which will enable them to rapidly and satisfactorily clip hair engaged thereby, thus, dispensing with the effort and labor incident to the operation of the ordinary manual clippers heretofore prevalent in the art.

Another and equally important object of the invention is to provide the clippers with a novel form of motion converting and transmitting connection whereby a reciprocal motion will be imparted to the movable clipping blade of the construction.

A further object of the invention resides in the provision of automatic clippers with a view to compactness, and in which the number of parts are few, the cost of production small, and efficiency and operation high.

Other improvements and novel details in the arrangement and construction of parts will be apparent from an inspection of the accompanying drawings in connection with the specific description hereinafter contained and wherein a preferred embodiment of the invention is shown for the purpose of illustration.

In the drawings:

Figure 1 is a plan view of the clippers having a part thereof broken away and shown in section; and

Fig. 2 is a vertical longitudinal section through the same.

Having more specific reference to the drawings and in connection with which like reference characters refer to corresponding parts throughout the several views, the construction includes a frame H substantially U shaped and having the forward portions thereof disposed obliquely to the body portion and converging as at h; a laterally disposed plate 1 being carried on said forward portions and having a downwardly disposed flange 2 formed on its forward marginal portion, the purpose of which will be subsequently described. Other flanges 3 are

formed rearwardly of the plate forming a housing and receiving a bearing pintle 4 therebetween, said pintle extending downwardly from an upstruck portion 5 of the plate 1. Finger pieces or holds 6 and 7 are also formed on the opposite sides of the U shaped frame H, and obviously serve to facilitate the holding and moving of the clippers.

Slidably engaging the under side of the plate 1 is a movable clipping blade 8 provided on its forward portion with the usual engaging and cutting teeth 8', while a longitudinal groove or way 9 is formed in the upper face thereof and serves to receive the flange formed on the forward portion of the plate 1, whereby to provide a guide for said blade during sliding or reciprocal movement thereof. A longitudinal slot 10 is also formed in the blade 8 and snugly and slidably receives guide pins 11 therein which pins are in turn carried upon the under side of the plate 1 and are of lengths slightly greater than the width of the movable clipping blade 8.

The lower side of the movable clipping blade 8 has a bearing on an immovable blade 12 also provided with the usual engaging and cutting teeth 12'. This plate 12 is formed with openings (not shown) in its intermediate portion to receive those portions of the pins 11 extending from the plate 1, in order that relative sliding movement between said immovable blade 12 and the plate 1 will be prevented.

For inter-connecting the several blades 8 and 12 and the plate 1, a bolt 13 is passed through each of the same, the head of said bolt being counter-sunk in the blade 12 while a nut (not shown) is engaged with the screw-threaded shank thereof. Of course, various forms of connections may be substituted, such as conditions or preference may dictate.

As means for permitting the transmission of motion to the blade 8 there is provided a lever 14 formed with a tapered forward extremity 14' loosely engaging the rear portion of the blade 8, and an offset rear extremity 14" in which there is formed a socket for slidably receiving a bar 15 having the rear end thereof pivoted to a bevel gear 20, hereinafter described.

To house the various active parts of the clippers a casing G in form of a handle hav-

ing its forward portion offset at g is provided and is adapted to be fitted into the frame H and preferably, to rest upon a shoulder 16 formed in and extending about the inner sides of said frame, as shown in the Fig. 2. A transverse bearing 17 is formed in the handle, which, as will be noted, has its under side dished, and serves as a bearing for a shaft 18 carrying a bevel pinion 19 in mesh with the gear 20 rotatably mounted in the dished side of said handle and having the adjacent end of the bar 15 pivoted thereto at 21 . The rear portion of the shaft 18 is preferably split as at 22 , to permit the engaging of a flexible shaft (not shown) thereto; a longitudinal web 23 being formed integral with the handle and arranged in the dished portion thereof having an opening through which said flexible shaft (not shown) is passed into engagement with the shaft 18 . A second and curved casing J is engaged over the oblique portions 14 of the frame having one end seated in the offset portion of the casing while the other end engages a portion of the plate 1 ; said casing J being secured in a fixed position by suitable means, not shown.

In operation, the frame H is held in the hand of a user, certain of the fingers engaging the pieces 6 and 7 . Rotary motion is transmitted to the gear 20 from whence it is converted to an oscillatory motion due to the connection of the link therewith and with the lever 14 . The lever in turn imparts a reciprocal motion to the blade 8

thus, causing functioning of the opposed teeth $8'$ and $12'$.

Manifestly, the construction shown is capable of considerable modification and such modification as is within the scope of my claim, I consider within the spirit of my invention.

What I claim is:

A pair of clippers, including a substantially U shaped frame having its forward portions disposed obliquely and converging, a lateral plate carried by said forward portions, a bearing pintle depending from the rear portion of said plate, movable and immovable blades in connection with said plate, a lever pivoted on said pintle having one portion loosely engaging the movable blade and the other portion offset and formed with a socket, a link slidably engaging said socket, a casing in the form of a handle having a dished side fitted in said frame, a bevel gear rotatably mounted in the dished side of the casing and pivotally connected to the adjacent end of said link, a pinion meshing with said gear for imparting motion thereto, and a second curved casing engaged over said oblique and converging portions of the frame and secured to said first casing.

In testimony whereof I affix my signature in presence of two witnesses.

RICCARDO DI CARLO.
